METHOD OF AND APPARATUS FOR PRODUCING CELLULAR AGGREGATE

Thorne E. Lloyd, Stanhope, N. J., assignor to Dwight & Lloyd Sintering Company, New York, N. Y., a corporation of Delaware

Application April 11, 1931. Serial No. 529,533

11 Claims. (Cl. 18—1)

This invention relates to a process and apparatus for heat treating material and provides for successively treating layers of said material to produce a light weight cellular aggregate.

5 The invention is particularly applicable to the burning of material, such as clay, shales, argillites and similar rocks which preferably have a relatively extended softening range, rather than a sharp melting point.

10 The process is so carried out that the various layers are each completely heat treated before the next successive layer is applied thereto and the product comprises a cellular cake which is substantially homogeneous and in which the various layers are joined together as an integral unit. The heat treatment may be carried out by applying hot gases to the various layers or by drawing the gases through the layers as they are successively passed through a heat treating apparatus.

The invention also consists in certain new and original features of construction and combinations of parts hereinafter set forth and claimed.

25 Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a side elevation of one form of apparatus for carrying on the improved process;

Fig. 2 is a plan view of the roof of the apparatus showing the arrangement of the apertures;

Fig. 3 is a sectional view taken on the line 40 3—3 of Fig. 1;

Fig. 4 is a side elevation of a modified form of apparatus for practicing the invention; and

Fig. 5 is a section taken on the line 5—5 of Fig. 4.

45 Like reference characters denote like parts in the several figures of the drawings.

In the following description and in the claims, various details will be identified by specific names for convenience, but they are intended to be as generic in their application as the art will permit.

The present process for manufacturing light cellular aggregate consists in heat treating a thin layer of raw material by passing there-

to bring the particles into the state of incipient fusion whereupon the particles are spun out into cellular form. A fresh layer of material is then applied which cools the first layer and causes it to retain its cellular form. The second layer is itself heated to the required temperature and the process is repeated until a bed of desired thickness has been built up whereupon it is discharged from the heating apparatus and may be crushed and screened to the desired size.

Referring to Figs. 1—3 an apparatus for carrying on this invention is shown which comprises a framework 10 carrying track 11 on which a plurality of movable pallets 12 are mounted. Said pallets are propelled along track 11 by driving wheel 13 operated by a source of power 14 through a gear train 15. Pallets 12 are preferably formed with side members 20 and perforated bottoms 21 (Fig. 3) which communicate with wind box 22. Said wind box is supported on frame 10 and is mounted directly beneath said pallets and is connected by suction pipe 23 to a suitable source of suction (not shown). Hinged doors 24 are provided for purposes of inspection or cleaning.

Supported on frame 10 and mounted above pallets 12 is a heating chamber 25 comprising roof 26, sides 27 and bottom members 28 which overhang the sides 20 of said pallets a sufficient distance to shield said sides from the intense heat of said chamber. Said bottom members 28 are preferably arranged sufficiently close to said pallets to form an effective seal and prevent leakage of gases. A further seal may be effected, if desired, by flexible members 30 which are secured to said side members and engage the sides of said pallets.

A plurality of burners 31 communicate with ports 32 which extend through sides 27 of said chamber. Said burners may be controlled by valves 33 and are fed through a header 34 in any convenient manner. It is to be understood that any suitable fuel, such as oil or gas, may be employed and the ports are preferably located a sufficient distance from the pallets to permit complete combustion before the gases come in contact with the bed of material. Valves 33 permit the regulation of the various burners so that control of the heat distribution within chamber 25 may be obtained.

Roof 26 is provided with a plurality of transverse apertures 38 which are arranged to distribute charge over the pallets 12 as they are moved through chamber 25. The apertures in the various rows may be staggered, so that the

piles of material dropped through any one row will not fall directly upon the piles dropped from the adjacent holes. A hopper 39 may be mounted in a convenient position to apply the charge to said roof. A plurality of movable rabbles 40 mounted on an endless belt 41 are adapted to engage said charge and distribute the same along said roof whereby it is applied to the various apertures and caused to fall there-through onto the pallets. Said belt 41 may be operated from power source 14 by any convenient drive such as belt 42. Side members 43 are mounted on roof 26 to confine the layer of material to the area above the apertures 38.

15 It is to be understood that the size of the apertures 38 may be varied to control the amount of material fed therethrough, for example, by the use of cast plates 60 having openings of various sizes which may be selectively positioned in said apertures.

Hopper 45 is also mounted on frame 10 in a position to discharge material to pallets 12 prior to their passage through heating chamber 25.

In the operation of the above described apparatus the interior of the heating chamber is kept filled with flame and hot combustion products by the fuel burners. A thin layer of prepared charge is fed onto the pallets from hopper 45 and is burned by the flame which is drawn through the charge into wind box 22. The first row of apertures 38 is positioned to drop additional charge on top of the bed as soon as the first material has been completely burned, and the other rows of apertures are likewise set so that each layer of material is burned before the next layer falls thereon. The particular arrangement of the apertures will depend upon the material being treated and upon the speed at which the pallets move through the heating chamber.

40 In preparing the charge, the material is preferably crushed sufficiently fine to pass a $\frac{1}{4}$ " screen and is moistened and thoroughly mixed to reduce the charge to small pellets, preferably grading from $\frac{1}{4}$ " to $\frac{1}{2}$ " down in size. As the charge in this form is dropped through the apertures onto the layer of material already in the pallet, it tends to spread out, even though dropped in a series of small piles, this tendency being increased by the generation of steam which 45 throws the pallets about violently when they are first subjected to the highly heated gases. In consequence, even though the charge is dropped on the layer at a few points spaced across its width, within a brief period of time it will have 50 spread into a comparatively uniform thin layer over the entire width of the pallet.

The second layer is applied immediately after the first layer has fused and expanded and before the material thereof has run together and lost its cellular condition. The second layer accordingly cools the first layer and causes it to remain in a cellular condition and also it is quickly heated to the fusion point and caused to firmly adhere to the first layer so that the final product comprises a homogeneous cake of considerable thickness and without cleavage planes or lines of fracture between the individual layers.

60 A modified form of apparatus for carrying on the invention is shown in Figs. 4 and 5. In this apparatus the frame 10, pallets 12, driving mechanism 14, hopper 45 and heating chamber 25 are similar in construction to that of Figs. 1-3 and have been given similar reference numerals. In 65 this form of apparatus, however, roof 26 is provided with a plurality of transverse slots 50, each

of which communicates with a feed hopper 51. Said feed hopper is provided with a discharge apparatus, such as rotating drum 52, by which a regulated quantity of material may be removed from the hopper and applied through slots 50 to the pallets. Shields 53 may be provided to prevent escape of gases from slots 50 as material is being applied thereto. The discharge apparatus may be driven by suitable gearing 54 which is connected to the driving motor 14 as by belt 55, and suitable gates 56 may be provided for controlling the amount of discharge from hopper 51.

70 The operation of this form of device is similar to that above described with the exception that the charge is fed from the various hoppers 51 through slots 50. This form of apparatus may be preferable in certain instances where an independent control of the rate of feed of the various layers is required.

75 A considerable variation in the product may be secured by suitable control of temperature and time of treatment given the charge. With high temperatures and rapid treatment a product is obtained having larger cells, but being somewhat less strong than that made with lower temperatures. It will be understood that the most suitable grade of aggregate will depend upon the particular use to which it is put and the various grades may be produced by proper control of the operating conditions. For example, an aggregate of maximum hardness will be desirable for making partition blocks, which require comparatively low strength, whereas a strong and somewhat heavier aggregate may be desirable for use in walls and floors which support a considerable load.

80 The herein described process for making light weight aggregate is rapid in operation, economical, requires but little labor and a comparatively small amount of fuel, makes an aggregate which is exceptionally light and extremely uniform in character and may be readily controlled for producing aggregate materials of various degrees of lightness and strength.

85 While certain novel features of the invention have been disclosed and are pointed out in the annexed claims, it will be understood that various omissions, substitutions and changes may be made by those skilled in the art without departing from the spirit of the invention.

90 What is claimed is:

1. The process of heat treating material to form an open cellular product which comprises successively treating superimposed layers of said material by drawing externally heated gases therethrough and substantially completing the treatment of each layer before the succeeding layer is applied thereto.

95 2. The continuous process of heat treating materials which comprises passing a layer of said material through a heating chamber, drawing externally heated gases through said material thereby effecting the desired heat treatment and applying additional layers of said material at spaced points in said chamber while continuing the heat treatment with externally heated gases so that each layer is completely heat treated before the next succeeding layer is applied thereto.

3. The method of heat treating materials which comprises passing said material in a thin layer through a heating chamber in which preheated gases are applied to and drawn through said material, progressively increasing the thickness of said layer as it advances through said heating

- chamber whereby the successive operations are successively subjected to said preheated gases.
4. The method of heat treating materials which comprises passing said material in a thin layer through a heating chamber and drawing preheated gases through said material to bring said layer to the state of incipient fusion and applying a second layer of material to said first layer before said first layer has melted and run together, said second layer serving to cool said first layer and maintain the same in its cellular condition and itself being heated to the fusion point by said gases and adhering to said first layer to form a uniform mass and repeating the operation with the addition of successive layers to form a mass of the desired thickness. 80
5. A heat treating apparatus comprising a heating chamber, a movable support, means for progressively passing said support through said chamber and means for applying layers of material to said support at spaced points as it is passed through said chamber and means for passing externally heated gases through said material whereby heat treatment of said layers is progressively effected. 85
6. An apparatus for heat treating materials comprising a heating chamber, a plurality of pallets having perforate bottoms, means for applying a layer of said material to said pallets and passing said pallets through said chamber, means for passing externally heated gases downwardly through said layer in said chamber and means for superimposing successive layers of said material thereon as said material advances through said chamber. 90
7. An apparatus for heat treating materials comprising a heating chamber, a plurality of pallets having perforate bottoms, means for applying a layer of said material to said pallets and passing said pallets through said chamber, means for passing externally heated gases downwardly through said layer in said chamber, means for superimposing successive layers of said material thereon as said material advances through said chamber, and means for regulating the thickness of each of said layers whereby the heat treatment thereof may be controlled. 95
8. In an apparatus for heat treating materials, a heating chamber, means for passing a layer of material through said chamber, burners for introducing hot gases to said chamber and causing complete combustion of said gases out of contact with said material and uniformly applying the heated gases over the surface of said material, means for drawing said hot gases through said material and means for superimposing successive layers of material as said material passes through said chamber at spaced points. 100
9. In a heat treating apparatus, a heating chamber, means for applying preheated gases thereto, a movable support for passing a layer of material through said chamber, a plurality of feeding means spaced along the roof of said chamber and adapted to apply successive layers of material to said support, and means for drawing said preheated gases through material passing through the preheated chamber on said movable support. 105
10. A heat treating apparatus comprising a heating chamber, a plurality of movable supports, means for passing said supports through said chamber, means for applying a charge of material to said supports and causing said charge to form a thin layer thereon, said heating chamber being provided with a roof having a plurality of transverse openings therein, means for applying a charge of material to said roof and means for spreading said material along said roof whereby it is caused to fall through said openings and to be applied to said movable supports in a plurality of successive thin layers. 110
11. A heat treating apparatus comprising a heating chamber, a plurality of movable supports, means for passing said supports through said chamber, means for applying a charge of material to said supports and causing said charge to form a thin layer thereon, said heating chamber being provided with a roof having a plurality of transverse openings therein, means for applying a charge of material to said roof, means for spreading said material along said roof whereby it is caused to fall through said openings and to be applied to said movable supports in a plurality of successive thin layers, said spreading means comprising a plurality of movable rabbles mounted on an endless belt and adapted to engage said charge and spread the same along said roof. 115
